Patented Oct. 4, 1927.

UNITED STATES PATENT OFFICE.

PHILIP A. REUTTER, OF WATERBURY, CONNECTICUT, ASSIGNOR TO SCOVILL MANUFACTURING COMPANY, OF WATERBURY, CONNECTICUT, A CORPORATION OF CONNECTICUT.

COMBINED REFILL AND PUFF HOLDER.

Application filed February 17, 1925. Serial No. 9,765.

This invention relates to certain improvements in vanity cases.

In certain types of the small boxes now widely used for carrying cosmetics and commonly known as vanity cases, the cosmetic, either rouge or powder, is in the form of a compact. This compact is a mass of powder associated with a binder, the compact material being usually molded on a plate or base of glass, aluminum or similar material, the article thus formed being known as the compact. In common types of vanity cases these compacts are what is known as refills, that is, after the compact is used up the base may be removed from the box and a fresh compact with its base inserted therein. To hold the compacts in the boxes, certain devices known as refill clips or plates are employed; these refill holders being provided with projections which are arranged to engage under some cooperating projection in the box and removably hold the clip in place. In vanity cases of the best form puffs or applicators are provided, these applicators usually occupying a position over the compact. To hold the puffs in position puff-holding devices have been employed in the form of separate plates with puff-holding projections arranged so as to overlie the puff and holding the puff in position.

A box thus constructed requires a considerable number of parts and takes time to assemble. It is the principal object of the present invention to produce a construction whereby the number of parts is reduced and a structure is provided in which the refill holder and the puff holder are combined in a unitary structure so that both material and time are saved in making and assembling the box.

With this and other objects not specifically referred to in view the invention consists in certain novel parts, arrangements and combinations which will be described in connection with the accompanying drawings and the novel features pointed out in the claims hereunto appended.

Referring now to the drawings—

Figure 1 is a central longitudinal section of one form of vanity case with the improved puff and refill holder in position, the case being shown open;

Figure 2 is a plan view, partly broken away, of the structure shown in Fig. 1;

Figure 3 is a partial vertical section on an enlarged scale, the section being taken on line 3—3 of Fig. 2; and,

Figure 4 is a perspective view of the combined puff and refill holder.

Referring now to these drawings, the invention, as above illustrated, includes a vanity case provided with a base and a cover in which there is provided a rouge compartment and a powder compartment located in the base, but it will be understood that the invention is in no way limited to such a case but will be capable of use with a case of any shape in which a compact or rouge is used with a refill holder and in which the box is provided with means for removably securing the holder in place.

Referring, however, to the box shown, which well illustrates the invention, there is provided a case having a cover 1 which may, if desired, be provided with a mirror, not shown and a base 2, these parts being pivotally associated on a hinge 3. The bottom and the cover are formed with flanges which have an oblique portion 4 and a vertical portion 5, the vertical portions abutting when the box is closed, a suitable catch, indicated at 6, being provided to hold the parts in position. One of the members, as the top, may have its side walls near one end formed with a pair of ears 7 which form a convenient grip for opening the box.

Within the box is positioned a plate 8 having a walled aperture 9 for the reception of a rouge compact. The walls 9 preferably extend to and rest on the bottom of the box. This plate is also formed with side and end flanges 10, 11, respectively, these flanges resting on the upper part of the inclined portion 4 of the bottom of the box, thus forming a stop for the plate. These side and end flanges are so proportioned as to extend slightly above the top of the wall so as to form a ridge or flange 12 over which the cover may telescope. The plate is also formed with an aperture 13 to receive a powder compact. The walls 14 of this aperture also preferably extend to the bottom of the box as indicated at 15 so that, in effect, two wells are formed for the compacts and the plate around the apertures is slightly turned in as indicated at 16, for a purpose hereinafter referred to.

These wells are capacitated to hold rouge and powder compacts and their refill hold-

ers. In accordance with the invention, a combined refill holder is provided, the holder seating in the wells in the box. While this holder may be constructed in various ways, so as to form a unitary structure, preferably for convenience in manufacture and ease in assembly, the compact and puff holder are integral.

In the particular construction shown 10 there is provided a base 17 in the form of a thin annular plate of light brass or other spring metal which is or may be provided with a central opening 18. Formed on this plate at opposite sides thereof is a pair of 15 compact holding projections. These projections are formed by striking out the metal to form legs 19 which are upwardly bent, as indicated at 20, then outwardly bent, as indicated at 21. These legs resiliently seat 20 under the inturned portion 16 of the plate before referred to and removably hold the compact in place. Also formed on the plate 17 and preferably integral therewith is a 25 puff-holding member. This puff-holding member, in the best constructions, comprises a pair of puff-holding devices and these devices are preferably arranged on one side of a diameter taken through the center of the plate so that the puff may be easily placed 30 in and removed from position. In the particular construction illustrated, therefore, there is provided two puff-holding devices 22, 23, spaced apart and arranged on one side of a diameter taken through the plate. Each 35 of these puff-holding devices comprises a projection 24 extending outwardly from the plate which is then bent upwardly as indi-

cated at 25 and then inwardly as indicated at 26. The plate being made of spring metal, these holders are of sufficient resiliency to give when a puff is inserted therein, and to hold the puff in position.

While the invention as above shown and described is considered to be its best form, it will be understood that certain changes and variations may be made in the specific structures shown and described without departing from the invention.

What I claim is:

1. A combined compact holder and puff holder comprising a base, a pair of spaced projections for holding a compact, and a pair of puff holders integral with the base and arranged between the compact holders.

2. In a vanity case, the combination with bottom and cover members of a flanged plate in one of the members provided with an aperture or well for a cosmetic, a shoulder on the inner wall of the well, and a cosmetic holder having compact holding projections engaging under the shoulder.

3. In a vanity case, the combination of bottom and cover members of a flanged plate in one of the members provided with an aperture or well for a cosmetic, a shoulder on the inner wall of the well, a cosmetic refill holder having compact holding projections engaging under the shoulder, and a puff holder integral with the refill holder and extending above the rim of the well.

In testimony whereof, I have hereunto set my hand.

PHILIP A. REUTTER.
